CYLINDER COCK

Curtis W. Ploen, Chicago, Ill., and Augustine R. Ayers, Shaker Heights, Cleveland, Ohio, assignors to The Okadee Company, Chicago, Ill., a corporation of Illinois

Application September 28, 1936, Serial No. 102,924

1 Claim. (Cl. 121—134)

The invention relates to automatic cylinder cocks.

One object of the invention is to provide an improved automatic cylinder cock which comprises a spring for opening the drain-valve, which is enclosed but located outside of the high temperature steam cavity of the cock. By reason of this location, the spring can not foul the movement of the cylinder cock in the event the spring becomes broken, can be easily examined and replaced without dismantling of the cylinder cock, and is not affected by the high steam temperatures in the cock.

Another object of the invention is to provide means located in the cap of the casing by which the drain-valve can be closed and kept closed in the event of a broken pipe in the line which supplies steam from the boiler for closing the drain-valve, while the engine is operated to permit the operation of the locomotive until repairs can be made, and also to close the cylinder cock when the locomotive is undergoing a hydrostatic test.

Another object of the invention is to provide a cylinder cock with a casing which is provided with a plurality of inlets which makes the cylinder cock symmetrically applicable to the right or left-hand cylinders, or to be differently positioned with respect to the cylinders.

Other objects of the invention will be apparent from the detailed description.

The invention consists in the several novel features which are hereinafter set forth and are more particularly defined by the claim at the conclusion hereof.

In the drawing: Fig. 1 is a side elevation of an engine cylinder having a pair of cylinder cocks respectively connected to the ends thereof. Fig. 2 is a horizontal section of the improved cylinder cock. Fig. 3 is a plan. Fig. 4 is a section on line 4—4 of Fig. 2.

The invention is exemplified in a cylinder cock comprising a casing 6; a valve 7 adapted to close against a seat 8; a piston 9 integrally formed with valve 7 and slidably mounted in a cylinder 10 formed in the casing 6; a head or plunger 11 integral with a stem, extending outwardly from valve 7 and through the valve-seat 8 and slidably guided in a cylinder 13 formed in an extension 13^a at one end of the casing 6; a drain-outlet 14 at the outer side of the valve-seat 8; a cap 15 screw-threaded into one end of casing 6 and coaxial with the cylinder 10; a cap 16 screw-threaded into and closing the outer end of extension 13^a of the casing at the opposite end of

the casing; a spring 17 between cap 16 and plunger 11 with its ends held in sockets in said cap and plunger for normally unseating the valve 7; a lateral offset 19 of the casing 6 containing a chamber 20 which communicates with the chamber 20^a around the valve 7; a pipe 21 connected to the offset 19 which leads from one end of the engine-cylinder 10 to subject one side of valve 7, when it is closed, to engine cylinder pressure; a pipe 18 threaded into one side of the casing 6 to deliver steam from the boiler to the cylinder 10 in the casing, for exerting pressure against it to close the valve 7 against the force of spring 17 and the steam under cylinder pressure acting on the other side of the piston 9. The differential areas on the opposite sides of piston 9 and valve 7 are such as to permit the engine-cylinder pressure, when it becomes excessive or abnormal, to open the valve 7 and relieve such pressure.

In practice, one of these cocks is applied to each end of the cylinder, as well understood in the art. Pipes 18 from the ends of the cylinders are connected to a common pipe 23, which leads to the engine-cap and is there provided with a valve for controlling the delivery of steam under boiler pressure to the cylinder 10 for operation of the piston 9 and valve 7, as well understood in the art. A port 13^b, provided in the bottom of the cylinder extension 13, serves as a small vent and also as a drain for any moisture.

In the operation of the improved cylinder cock, the spring 17 will keep valve 7 unseated except when steam is delivered under boiler pressure through pipe 18 to the cylinder 10 at one side of the piston 9. The valve 7, when the engine is not operating, will be open and will permit the cylinder to drain through the cylinder cocks. The valve 7 will remain open while the engine is in operation until the engineer opens the valve 24 in the cab to admit steam from the boiler which is greater than cylinder pressure, into one side of cylinder 10. This will shift piston 9 to the left and force the valve 7 against its seat 8. If, during the operation of the engine and while the valve 7 is closed, any excessive or abnormal condition develops in the cylinder, such as a slug of water, the pressure in chamber 20^a will be sufficient to force the piston 9 to the right against the force of the steam in the outer end of cylinder 10, thus eliminating the possibility of damage to the cylinders and working machine. When the steam is cut off from pipe 18 and cylinder 10 the cock will be kept open to drain the engine cylinders.

The location of the spring is an important fea-

ture because it is located outside of the high temperature steam cavity 20^a in the casing 6. When the spring is located in the high temperature steam cavity around the valve 7, it is subjected to superheated steam temperatures, which is likely to cause breakage and if the spring becomes broken when located in such cavity, it sometimes fouls the movement of the valve. In the construction set forth, the spring 17 is located because it is located outside of the high temperature because it acts on a plunger on the valve stem 12 which is located in an extension of the casing beyond the drain cavity 14. This location also makes it possible to readily examine the spring upon removal of the cap 16 and to readily replace the spring without dismantling the cylinder cock. The valve seat 8 is formed in a ring 8^a of heat-treated non-corrosive metal, which is pressed into a socket in the casing and around the ring.

In practice, it sometimes occurs that it is desirable to close the cylinder cock, for example, in the event of a broken steam pipe. It is also necessary to close the cylinder cock when the locomotive is undergoing a hydrostatic test. In order to permit the valve to be held closed, a screw 26 extends, and is threaded, through the cap 15 and is provided at its outer end with a polygonal terminal whereby the screw may be turned and at its inner end with a head 28 which is adapted to engage a stem 29 integral with the piston 9 and valve 7. By turning the screw 26, its head 28 will engage the stem 29 and force the valve 7 against its seat. A lock-nut 30 is applied to the outer end of screw 26 so that the screw may be securely locked in its inoperative position. The head 28 is provided with an inwardly flared annular face and the cap is provided with a correspondingly tapered annular seat against which the face on the head can be

forced by the screw. This makes it possible to prevent the leakage of steam around the screw without the use of packing and by screwing the flared face tightly against the seat.

In practice, it is desirable to adapt the cock 5 so it can be reversibly positioned with respect to the engine cylinders. For this purpose, the off-set 19 of the casing is provided with a screw-threaded opening 32 in both the upper and lower walls of the off-set 19. A screw-plug 33 is adapted to close one of the openings while a pipe 21 is connected to the other. The plug 33 and the pipe 21 may be screwed into either wall of the casing as desired, so the casing can be reversed with respect to the engine.

The invention is not to be understood as restricted to the details set forth, since these may be modified within the scope of the appended claim, without departing from the spirit and scope of the invention.

Having thus described the invention, what we claim as new and desire to secure by Letters Patent is:

In an automatic cylinder-cock, the combination of a casing provided with a drain-port, a piston within the casing, means for communicating boiler-pressure to one side of the piston and cylinder-pressure to the other side, a valve operable by said piston to close the drain-port, a spring for opening the valve, a cap at one end of the casing, and a screw in the cap for manually closing the valve, the screw having a head at its inner end provided with an inwardly flared annular face, the cap having a correspondingly tapered annular seat against which the face on the head can be forced by the screw to prevent the leakage of steam around the screw.
